Primary Examiner — George J Ulsh*Assistant Examiner* — Jihyung Yoon(74) Attorney, Agent, or Firm — Panitch Schwarze Belisario & Nadel LLP(57) CLAIM

The ornamental design for a flush-mounted fireplace frame as shown and described.

DESCRIPTION

The sole FIGURE is a front elevational view of the flush-mounted fireplace frame in accordance with my new design. The broken lines in the FIGURE show portions of the flush-mounted fireplace frame which form no part of the claimed design.

Only one view of the flush-mounted fireplace frame is shown in the drawing. It is understood that the appearance of any part of the article not shown in the drawing or described in the specification forms no part of the claimed design. Those portions of the flush-mounted fireplace frame not shown in the sole FIGURE form no part of the claimed design. In re Zahn, 617 F.2d 261, 204 USPQ 988 (CCPA 1980)
